United States Patent Office

Des. 183,639
Patented Sept. 30, 1958

183,639

RING

Pierre J. Touraine, Alhambra, Calif.

Application November 8, 1957, Serial No. 48,383

Term of patent 7 years

(Cl. D45—10)

FIG. 1.

FIG. 3.

FIG. 2.

FIG. 4.

FIG. 5.

Fig. 1 is an enlarged perspective view of a ring embodying my new design;

Fig. 2 is a plan view of the ring;

Figs. 3 and 4 are side elevational views of the ring; and Fig. 5 is a front elevational view of the ring.

I claim:

The ornamental design for a ring, as shown.
